[57] CLAIM

The ornamental design for a mobile telephone set, as shown and described.

DESCRIPTION

FIG. 1 is a front, bottom and right side perspective view of a mobile telephone set showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a front elevational view thereof showing handset separated from stand; and, FIG. 9 is a front, bottom and left side perspective view thereof as shown in FIG. 8. The telephone cord shown by means of dot-dash line throughout the views is continuous throughout.

FIG. 1

FIG.2

FIG.3

FIG.4

FIG.5

FIG.6
